UNITED STATES PATENT OFFICE.

DORSEY F. ASBURY, OF BROOMES ISLAND, MARYLAND.

RADIO APPARATUS.

Application filed February 16, 1927. Serial No. 168,799.

My invention relates to radio apparatus and has particular reference to improvements in operating means for the movable parts of tuning units, such, for example, as 5 variable plate condensers, my object, generally speaking, being to provide an operating means of simple, inexpensive construction whereby the movable parts of a plurality of tuning units may be connected together for 10 convenient collective and individual operation for the various purposes set forth in my prior applications serially numbered 683,756; 689,338; 10,293; 72,514; 80,833; 89,443; 91,197; 95,138; 98,558; 108,074; 155,016 15 and 166,516 and in my Patents 1,598,415; 1,590,441; 1,605,804 and 1,605,805.

It is old, as disclosed in my prior applications 80,833 and 166,516 for example, to provide an operator having two different 20 forms of movement to move the movable parts of a plurality of tuning units collectively. It also is old, as disclosed in said application 80,833, to provide means to cause one form of movement of a two movement 25 operator to impart the other form of movement thereto. A two movement operator is beneficial in itself for various reasons some of which are set forth in said prior applications, and the provision of means to cause 30 one form of movement to impart the other form of movement to a two movement operator also is beneficial for various reasons as will become particularly apparent from a perusal of application 80,833. However, the 35 means disclosed in application 80,833 for causing one movement to produce the other movement of the two movement operator thereof consists of a cam which controls continuously each form of movement of the 40 operator with respect to the other form of movement thereof and therefore does not permit such an amount of either form of movement of the operator individually as would permit the user of the apparatus to 45 test the accuracy of the shape of the cam to establish a pretuned relation of the tuning units for all wave lengths. It is therefore my present purpose to provide in connection with a two movement operator 50 means to cause one form of movement thereof to impart the other form of movement thereto and at the same time permit such an amount of one of said forms of movement independently of the other as will permit the user of the apparatus to test the accuracy of the adjustment of such means to establish a pretuned relation of the tuning with different wave lengths. 55

Specifically my present improvements consist in the provision of spaced adjustable 60 devices effective to produce one form of movement of a two movement operator intermittently during continuous movement of the operator by the other form of movement thereof, the result being that the tuning 65 units may be pretuned accurately with certain spaced wave lengths throughout the wave scale and pretuned approximately and sufficiently accurate for all ordinary purposes with all remaining wave lengths in 70 the wave scale and yet the operator is capable of being moved at any time to test the accuracy of the adjustment of said devices.

Other purposes as well as the nature and advantages of my improvements will be 75 become more fully apparent from a perusal of the following description considered in connection with the accompanying drawings, in which:—

Fig. 1 is a front elevation of a plural 80 tuning unit radio apparatus showing a preferred form of my improved operating means associated with the movable parts of the tuning units thereof;

Fig. 2, a horizontal section through the 85 apparatus illustrated in Fig. 1;

Fig. 3, a central vertical section through the apparatus shown in Figures 1 and 2;

Fig. 4, a detail perspective of an element of my improved apparatus; 90

Fig. 5, a sectional view showing a modified form of my improved operating means;

Fig. 6, a section on the line 6—6 of Fig. 5;

Fig. 7, a view similar to Fig. 2 showing a further modified embodiment of my im- 95 proved operating means.

Fig. 8, a section on the line 8—8 of Fig. 7; and

Fig. 9, a central vertical section through a portion of the structure shown in Fig. 7. 100

Referring to the drawings in detail, it will be observed that the tuning units the movable parts of which are intended to be operated by my improved operating mechanisms

are indicated in the disclosure of each form of my invention as variable plate condensers, each including, as usual, a set of stator plates *a* and a set of rotor plates *b*, the latter constituting the movable parts of said units. It is to be understood, however, that the tuning units are illustrated herein as variable plate condensers merely for convenience, since they may be of any other form, such, for example, as coils, the only essential being that each of them include a part movable to effect tuning thereof with different wave lengths in order that my improved mechanisms may be adapted to their operation.

- 15 In a preferred embodiment of my invention as disclosed in Figures 1 to 4, the tuning units, two in number, are mounted in any suitable manner upon any suitable support such as a base board 10 in side by side spaced relation and with the axes of their rotor shafts 12 disposed in parallelism. On an end of the rotor shaft of one unit is fixed a spur gear 14 and on the corresponding end of the rotor shaft of the other unit is fixed a spur gear 16. A shaft 18, located between the tuning units and disposed normally in parallelism with the rotor shafts of said units, is pivoted at one end as at 20 to a bracket 22 secured to the base 10 for swinging movement in a plane at right angles to a plane including the axes of the rotor shafts of the tuning units, and upon the other end portion of said shaft is rotatably mounted a knob or dial 24 which extends through an opening 26 in a panel board 28 to the exterior of the apparatus where it may be grasped for manipulation. Opening 26 is elongated in the direction of pivotal movement of shaft 18 and one side wall 30 thereof is disposed substantially in alinement with the pitch line of the teeth of gear 14 while the other side wall 32 thereof is disposed substantially in alinement with the pitch line of the teeth of gear 16, this for a purpose which will presently appear. A spur pinion 34 carried by the knob or dial 24 is located between and in mesh with the spur gears 14, 16, the normal looseness or play between the teeth of said pinion and gears permitting the knob or dial to be moved laterally a slight amount sufficient to bring a circular portion 38 thereof against either wall 30 or 32. A friction device indicated generally at 40 serves to resist pivotal movement of shaft 18, so that it will remain in any pivotally adjusted position in which it is placed said device 40 being secured to a fixed support such as base board 10 and including, as shown in Figure 4, a pair of yieldable arms 42, 42 between which the shaft is slidable, the normal distance between said arms being less than the diameter of the shaft whereby the necessary friction is afforded by said arms to resist pivotal movements of the shaft.

16 Friction device 40 serves to maintain shaft

18 normally midway between the rotor shafts of the tuning units so that the cylindrical surface 38 of the knob or dial 24 is spaced slightly from both of the side walls 30, 32 of the opening 26, said shaft being capable of slight flexure, however, so that by pressing laterally upon said knob or dial its afore-said cylindrical surface may be moved into engagement with either of the walls 30 or 32 of said opening 26. As a result of this arrangement it is apparent that knob or dial 24 has two different forms of movement by which the spur gears 14, 16 and consequently the movable parts of the tuning units may be moved collectively, one of said forms of movement being rotation when the cylindrical surface 38 is spaced from both of the walls 30, 32 and the other being a body movement in a direction at right angles to a plane including the axes of the rotor shafts of the units, the latter form of movement being permitted by pivoting the shaft 18 as at 20 and by elongating the opening 26 in the direction of pivotal movement of said shaft as aforesaid.

The tuning units are duplicates of one another, but are arranged in reversed relation, so that rotation of pinion 34 in one direction will serve to increase the amount of overlap between the rotor and stator plates of both units and rotation of said pinion in an opposite direction will serve to decrease the amount of overlap between the rotor and stator plates of both units. Consequently it follows that by bodily shifting the knob or dial 24 in either of its two permissible directions, the amount of overlap between the rotor and stator plates of one unit will be increased and the amount of overlap between the rotor and stator plates of the other unit will be decreased. In other words, it may be said that rotation of the knob or dial 24 will impart movements to the movable parts of the units to secure like tuning results from each of them, while movement of said knob or dial bodily will impart movements to the movable parts of the units to secure unlike tuning results therefrom. On the other hand, by pressing the knob or dial slightly laterally in one direction, its cylindrical surface 38 will be caused to contact with the wall 30, so that by then rotating said knob or dial while maintaining its cylindrical surface 38 in contact with said wall a rolling action of the knob against said wall will occur and spur pinion 34 as a result will, in effect, pivot about spur gear 14 and as a consequence rotate spur gear 16 individually, spur gear 14 remaining stationary due to the wall 30 being alined with the pitch line of the teeth of said gear, so that as the knob rolls against said wall, pinion 34 also rolls against gear 14. By pressing the knob laterally in an opposite direction and simultaneously im-

parting a rotary movement thereto, cylindrical surface 38 will roll on wall 32 and as a consequence pinion 34 will pivot about gear 16 with resultant individual rotation of 6 gear 14.

It will be noted that when the knob or dial is rolled against either wall 30 or 32 the spur gear which is alined with the wall against which the knob or dial is rolled 10 will be held against rotation by the pinion 34 due to the rolling action of the latter against the gear.

As a result of the arrangement of parts having the mode of operation described in 15 the foregoing the manipulation necessary to tune both of the tuning units accurately with any particular wave length is apparent; first, the knob or dial 24 is rotated to move the movable parts of the units collectively until each is approximately in tune 20 with the wave length desired. When this has been done the operator then may be shifted bodily to increase the capacity of one unit and decrease the capacity of the 25 other if this is necessary to bring each unit accurately in tune with the desired wave length, or, if one unit has been tuned accurately with the desired wave length as a result of the collective operation and only 30 the other unit requires further adjustment to bring it into accurate tune with the same wave length, operation of the individual unit requiring adjustment may be effected by rolling the knob against one or the other 35 of the walls 30 or 32.

Since the pinion 34 is located between and remains at all times in mesh with the gears 14, 16 and since the latter are rotatable in opposite directions to accomplish the same 40 tuning effects in each unit, it follows that the knob or dial 24 can have only a single definite position when each unit is accurately tuned with any particular wave length, and this being true it follows that the various 45 definite positions assumed by the knob when the apparatus is in accurate tune with different wave lengths, respectively, may be logged or indicated, so that whenever it is desired to tune the apparatus with a particular wave length all that is necessary is 50 to move the operator to the single definite position it can occupy when the units are in tune with that wave length. In other words, since the knob 24 must have a definite position 55 of rotation as well as a definite position bodily when both units are in tune with a particular wave length, it is manifest that once the correct rotated and bodily moved positions of the knob are known for correct 60 tuning of the units with a particular wave length any suitable means may be employed for indicating these positions, so that if subsequently it is desired to tune the apparatus with that particular wave length, such tuning 65 may be accomplished instantly simply

by positioning the knob in a definite position through the instrumentality of said indicating means. However, instead of providing means merely to indicate the correct position of the knob or dial 24 to secure accurate 70 tuning of both tuning units with any particular wave length, as proposed in my application 166,516, I now provide means which, during rotation of the knob or dial, will automatically move the same bodily the 75 amount necessary to bring both units accurately in tune with different wave lengths encountered by the units during rotation of the knob or dial. A preferred form of such means may consist, as shown in the drawings, of a pair of spaced abutment members such as rollers 44, 44 secured to the panel board 28, and a series of devices such as disks 46 mounted eccentrically on the knob or dial 24 and spaced circumferentially 80 around the latter, said devices, during rotation of the knob or dial, being adapted to pass successively between the rollers 44, 44 and by engagement with the latter serving to move the dial and consequently the pinion 34 bodily in one direction or the other, either upward or downward as shown in Fig. 1 to bring the units accurately in tune with the particular wave length encountered when any given disk 46 is located between the rollers 44, 44. The disks are eccentrically mounted on screws 48 which pass through the knob or dial and are threaded into the disks, so that the latter may be adjusted and secured in different adjusted positions to 90 produce a greater or lesser amount of body movement of the knob or dial as may be required for any given amount of rotary movement thereof to secure accurate tuning of the units with different wave lengths. To 95 secure proper adjustment of the disks the several screws 48 are loosened and the knob or dial is rotated until one of the disks is positioned between the rollers 44, 44, at which time the units will be approximately 100 in tune with a wave length. The knob or dial then is manipulated in the manner 105 aforementioned to individually adjust first one and then the other of the units to bring each of them accurately in tune with that 110 wave length. This will result in the operator assuming the one definite position it can occupy when both units are accurately 115 in tune with the wave length, all that then is necessary being to tighten the screw 48 to 120 lock the disk 46 against movement. The knob or dial then is rotated until the next disk is located between the rollers 44, 44 and the same operation is repeated. When 125 all of the disks have been adjusted and locked against movement the apparatus thus is pretuned with certain spaced wave lengths in the wave scale and pretuned approximately with all other wave lengths in the wave scale, this because the disks 46 are 130

placed relatively close to one another so that the amount of body movement of the knob or dial for an amount of rotary movement thereof equal to the distance between any two disks necessary to secure accurate tuning of the units with different wave lengths is so slight that proper adjustment of any one disk not only means that the units are pretuned accurately with the wave length 10 encountered when that disk is between the rollers 44, 44, but that they are tuned sufficiently accurate for all ordinary purposes with wave lengths encountered when, by rotation of the knob or dial, the disk is not 15 between, but only adjacent to the rollers, friction device 40 serving to hold the knob or dial against body movement at such times during rotation thereof that the disks do not engage the rollers, so that the body adjustment of the knob or dial effected by any given disk is maintained until the next disk moves between the rollers. By reason of the relative spacement of the disks the knob or dial is free to be moved bodily whenever a 20 disk is not located between the rollers, so that the accuracy of the adjustment of the disks may be tested whenever desired.

In Figures 5 and 6 of the drawings I have shown my present improvements associated with an operator of the type disclosed in my application 80,833, that is, with an operator having two different forms of movement, one of which is reciprocation and the other is tilting movement to move 30 the movable parts of the tuning units with which it is associated. In this form of my invention the tuning units are mounted in spaced relation with their rotor shafts disposed in parallelism and equipped, respectively, with spur gears 14', 16', the operator for said units being in the form of a double rack bar 50, the teeth along one side of which mesh with one of said gears and the teeth along the other side of which mesh with 40 the other of said gears, it being apparent that by moving said bar longitudinally the gears 14', 16' will be rotated in opposite directions equal amounts collectively which, due to the reversed relation of the tuning 45 units, will impart the same tuning movement to each of them, and that by tilting said bar the gears will be rotated in the same direction, both clockwise or counter clockwise as the case may be, and unlike tuning 50 movements will result. On said bar I mount a pair of rollers 52, 52 and to any suitable support 54, fixed with respect to the apparatus, I mount eccentrically in relative spaced relation a series of disks 56, adapted 55 to be engaged successively by said rollers as the bar is moved longitudinally to impart the necessary tilting movement thereto to bring the tuning units accurately in tune with the wave length encountered when any 60 particular disk is between said rollers.

Adjustment of the disks in this instance is effected in the same manner mentioned in respect to the disks 46 in the embodiment of my invention shown in Fig. 1, and a friction device, indicated generally at 58, is 70 provided to hold the bar against tilting movement during such longitudinal movement thereof as when the rollers 52 are travelling between any two disks 56. As shown, friction device 58 may consist of a 75 block 60 engaging within a slot 62 in the bar 50, so that the bar may be moved longitudinally with respect thereto, a pair of spring arms 64 secured to support 54 and frictionally engaging said block serving to 80 resist movement thereof in the direction of tilting movement of the bar.

In Figures 7 to 9 of the drawings I have illustrated a further modification of my present invention to show primarily that a 85 two movement operator is capable of operating more than two tuning units collectively and individually in pretuned relation to one another. This form of my invention is the same as the form shown in Fig. 1 with the 90 exception that the end of the shaft 18 opposite the end thereof on which the knob or dial 24 is mounted, instead of being pivoted to a fixed support, has mounted thereon a spur pinion 66 meshing with a spur gear 68 95 on the rotor shaft of a third tuning unit indicated generally at 70. Also, instead of a cylindrical surface 38 being provided on the knob or dial as in the disclosure of Fig. 1, a pair of screws 72 are threaded into the 100 panel 28 in such position with respect to the spur gears 14, 16 that either or both of these gears may be locked by said screws against rotation. The end of shaft 18 which carries pinion 66 is capable of lateral movement in a direction which will result in rotation of spur gear 68 by said pinion provided the latter is held against rotation, but such lateral movement of said shaft normally is resisted by a friction device indicated generally at 74. On pinion 66 is mounted eccentrically a series of disks 76 which are 105 spaced circumferentially around said pinion, these disks being adapted for cooperation with a pair of rollers 78, 78 mounted on any suitable fixed support 80. A screw 82 serves as a means of locking pinion 66 against rotation. As a result of this arrangement it is manifest that with each of the screws 72, 82 loosened, rotation of the knob or dial 24 110 will result in collective rotation of the movable parts of all of the tuning units. If, however, one of the screws 72 is tightened to hold, say, spur gear 14 against rotation, and if at the same time screw 82 is tightened to 115 hold pinion 66 against rotation, rotation of the knob or dial 24 then will result in pinion 34 rolling against gear 14 and pinion 66 rolling against spur gear 68 with consequent 120 individual rotation or adjustment of spur 125 130

gear 16. On the other hand, by tightening the forms of movement of said operating member intermittently during continuous movement of said operating member by the other form of movement thereof.

5 3. In radio apparatus, a plurality of adjustable tuning units, an operator having two different forms of movement one of which is rotation, connections between said operator and said units responsive to either form of movement of said operator independently of the other to adjust said units collectively, and means to cause continuous rotation of said operator to impart the other form of movement thereto intermittently.

10 4. In radio apparatus, a plurality of adjustable tuning units, an operating member having two different forms of movement, connections between said operating member and said units responsive to either form of movement of said operating member independently of the other to adjust said units collectively, a fixed member adjacent to said operating member, spaced devices carried by one of said members, an element carried by the other of said members adapted for successive cooperation with said spaced devices to produce one of the forms of movement of said operating member intermittently during continuous movement of said operating member by the other form of movement thereof, and means frictionally holding said operating member against its first mentioned form of movement when said element is disposed between any two of said spaced devices.

15 5. In radio apparatus, a plurality of adjustable tuning units, a rotatable and laterally movable operator, connections between said operator and said units responsive to rotary and lateral movements of said operator independently of one another to adjust said units collectively, and means for causing one of the movements of said operator to impart the other movement thereto.

20 6. In radio apparatus, a plurality of adjustable tuning units, an operating member having two different forms of movement, connections between said operating member and said units responsive to either form of movement of said operating member independently of the other to adjust said units collectively, a fixed member adjacent to said operating member, spaced devices carried by one of said members, an element carried by the other of said members cooperating with said spaced devices to produce one of the forms of movement of said operating member intermittently during continuous movement of said operating member by the other form of movement thereof, and means for adjusting said spaced devices to vary the amount of movement imparted by them to said operating member.

25 7. In radio apparatus, a plurality of adjustable tuning units, a rotatable and later-

the shaft 18 carrying the pinion 66. Thus, in the light of the explanation given in respect to the disclosures in the preceding figures of the drawings, it is apparent that by means of two sets of adjustable disks, one set on the dial 24 and the other set on the pinion 66 a single, two movement operator may be adapted to the pretuned operation of three tuning units, the disks on the pinion 66 serving to move this pinion the correct amount laterally at the same time the disks on the knob or dial move the pinion 34 bodily during rotation of the knob or dial to cause all units to tune simultaneously and accurately with different wave lengths encountered by the units during their collective movement resulting from rotation of the knob or dial.

30 From the foregoing description considered in connection with the accompanying drawings it is believed that the construction, operation and advantages of my improvements will be fully understood. I desire to point out, however, that various changes and desirable additions may be made in and to the structures shown within the spirit and scope of my invention as defined in the appended claims.

I claim:

1. In radio apparatus, a plurality of adjustable tuning units, an operator having two different forms of movement one of which is rotation, connections between said operator and units responsive to either form of movement of said operator independently of the other to adjust said units collectively, and means for causing one of the forms of movement of said operator to produce the other form of movement thereof.
2. In radio apparatus, a plurality of adjustable tuning units, an operating member having two different forms of movement, connections between said operating member and said units responsive to either form of movement of said operating member independently of the other to adjust said units collectively, a fixed member adjacent to said operating member, spaced devices carried by one of said members, and an element carried by the other of said members cooperating with said spaced devices to produce one of the forms of movement of said operating member intermittently during continuous movement of said operating member by the other form of movement thereof, and means for adjusting said spaced devices to vary the amount of movement imparted by them to said operating member.
3. In radio apparatus, a plurality of adjustable tuning units, an operator having two different forms of movement one of which is rotation, connections between said operator and units responsive to either form of movement of said operator independently of the other to adjust said units collectively, and means to cause continuous rotation of said operator to impart the other form of movement thereto intermittently.
4. In radio apparatus, a plurality of adjustable tuning units, an operating member having two different forms of movement, connections between said operating member and said units responsive to either form of movement of said operating member independently of the other to adjust said units collectively, a fixed member adjacent to said operating member, spaced devices carried by one of said members, an element carried by the other of said members adapted for successive cooperation with said spaced devices to produce one of the forms of movement of said operating member intermittently during continuous movement of said operating member by the other form of movement thereof, and means frictionally holding said operating member against its first mentioned form of movement when said element is disposed between any two of said spaced devices.
5. In radio apparatus, a plurality of adjustable tuning units, a rotatable and laterally movable operator, connections between said operator and said units responsive to rotary and lateral movements of said operator independently of one another to adjust said units collectively, and means for causing one of the movements of said operator to impart the other movement thereto.
6. In radio apparatus, a plurality of adjustable tuning units, an operating member having two different forms of movement, connections between said operating member and said units responsive to either form of movement of said operating member independently of the other to adjust said units collectively, a fixed member adjacent to said operating member, spaced devices carried by one of said members, an element carried by the other of said members cooperating with said spaced devices to produce one of the forms of movement of said operating member intermittently during continuous movement of said operating member by the other form of movement thereof, and means for adjusting said spaced devices to vary the amount of movement imparted by them to said operating member.
7. In radio apparatus, a plurality of adjustable tuning units, a rotatable and later-

ally movable operator, connections between said operator and said units responsive to rotary and lateral movements of said operator independently of one another to adjust said units collectively, spaced members carried by said operator, and a fixed member with which said spaced members successively

coact during rotation of said operator to impart lateral movements thereto intermittently.

10

In testimony whereof I hereunto affix my signature.

DORSEY F. ASBURY.
